By *A. B. Williamson & Co.*

UNITED STATES PATENT OFFICE.

HARRY B. ROUSE, OF CHICAGO, ILLINOIS.

PRINTER'S COMPOSING-STICK.

SPECIFICATION forming part of Letters Patent No. 680,547, dated August 13, 1901.

Original application filed March 23, 1900, Serial No. 9,922. Divided and this application filed September 20, 1900. Serial No. 30,575. (No model.)

To all whom it may concern:

Be it known that I, HARRY B. ROUSE, a citizen of the United States, residing at Chicago, in the county of Cook and State of Illinois, 5 have invented certain new and useful Improvements in Printers' Composing-Sticks; and I do declare the following to be a full, clear, and exact description of the invention, such as will enable others skilled in the art 10 to which it appertains to make and use the same.

This invention relates to improvements in printers' composing-sticks of the class known in the art as "job-sticks," adapted for quick 15 adjustment to different widths of columns; and the present application (Case C) is a division of an application filed by me March 23, 1900, Serial No. 9,922.

The object of the invention is to provide a 20 composing-stick of the character specified having simple and effective locking and adjusting means by which the knee may be quickly and accurately adjusted to any standard measure.

25 With this and other minor objects in view the invention consists of certain novel features of construction, combination, and arrangement of parts, which will be hereinafter more fully described, and particularly 30 pointed out in the appended claim.

In the accompanying drawings, Figure 1 is 35 a perspective view of the composing-stick embodying my invention. Fig. 2 is a bottom plan view of the knee. Fig. 3 is a transverse section on line 3-3 of Fig. 2.

Referring now more particularly to the drawings, wherein like reference characters designate corresponding parts throughout the several views, the numeral 1 denotes the body 40 of the stick, comprising a base 1', a side wall 2, and an end wall 3. The side wall is formed with a longitudinal row of dog-seats, which in the present instance are shown in the form of straight rack-teeth 4, located at the junction of the side wall 2 with the base of the stick. It does not necessarily follow, however, 45 that the seats should be thus arranged, and I do not therefore desire to be limited to such construction. I prefer, however, to form

these seats in the front face of a bar 4', interposed between the base 1' and side wall 2 and forming the base of said side wall, as this construction permits of the use of cast or sheet metal for the side wall and base and of a harder and more durable form of metal for 55 the bar, which sustains the wear.

5 denotes the knee of the composing-stick, comprising the integral arms 6 and 7, arranged at right angles and connected near their outer ends by an integral diagonal 60 brace 8. Upon the outer edge of the arm 7 is mounted a fixed or integral dog, consisting of one or more fixed or integral teeth 9, which are preferably tapered near the end to facilitate adjustment of the knee and are designed 65 to coact with the seats 4, formed in the side wall of the body portion of the stick, as shown clearly in Fig. 2. The teeth are preferably formed at the end of the arm 7 adjacent to the arm 6, the remainder of the abutting face of said arm being plane-surfaced in order that the knee may be adjusted with the expenditure of a minimum amount of time and labor and gage the position of the knee accurately. The knee is adapted to be 70 secured by a clasp or fastener 10, pivoted to the arm 7 of the knee and provided with a handle 11 with which to operate it. When swung down in position, the clasp embraces the arm 7 and the side wall 2 of the body of 75 the stick and securely holds the two in place. In practice the seats are spaced a determined distance apart, say a pica or half-pica from center to center of said seats, so that by 80 means of the dog the knee may be quickly 85 and conveniently adjusted to any standard measure. The teeth of the dog are preferably tapered, as stated. This insures a firm seat on the side of the teeth and at the same time centers the knee at the desired measure. 90

From the foregoing description, taken in connection with the accompanying drawings, the construction, operation, and advantages of the invention will be readily understood without requiring an extended explanation. 95

Changes in the form, proportion, and the minor details of construction may be made within the scope of the invention without de-

parting from the spirit or sacrificing any of the advantages thereof.

Having thus fully described my invention, what I claim, and desire to be secured by Letters Patent, is—

In a printer's composing-stick, the combination of a body comprising a base, side and end walls, and a bar interposed between said base and side wall and formed with seats,

and a knee provided with a dog to engage in said seats, substantially as described.

In testimony whereof I have hereunto set my hand in presence of two subscribing witnesses.

HARRY B. ROUSE.
